US0D1007380S

(12) **United States Design Patent** (10) **Patent No.:** **US D1,007,380 S**
(45) **Date of Patent:** **** Dec. 12, 2023**

(54) **GRILLE PANEL**

(71) Applicant: **PACCAR Inc**, Bellevue, WA (US)

(72) Inventors: **David Leetz**, Denton, TX (US); **Troy R. McCuller**, Argyle, TX (US)

(73) Assignee: **PACCAR Inc**

(**) Term: **15 Years**

(21) Appl. No.: **29/799,684**

(22) Filed: **Jul. 15, 2021**

(51) LOC (14) Cl. **12-16**

(52) U.S. Cl.

USPC **D12/163**

(57) **CLAIM**

The ornamental design for a grille panel, as shown and described.

DESCRIPTION

FIG. 1 is a perspective view of a grille panel embodying our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines shown in the drawings depict portions of the grille panel that form no part of the claimed design.

1 Claim, 4 Drawing Sheets
